(57) **CLAIM**

The ornamental design for a combined hand-held health monitoring and diagnostic device, as shown and described.

DESCRIPTION

FIG. 1 is a front perspective view of a combined hand-held health monitoring and diagnostic device, showing our new design, in open position;

FIG. 2 is a top view thereof, in closed position;

FIG. 3 is a front view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof, in open position.

The broken line showing in FIGS. 1-8 is for illustrative purposes only and forms no part of the claimed design.
